(57) CLAIM

The ornamental design for a tile-line logo, as shown and described.

DESCRIPTION

FIG. 1 shows a perspective view of a tile-line logo;

FIG. 2 shows a front view of the tile-line logo.

FIG. 3 shows a top view of the tile-line logo; and,

FIG. 4 shows a side view of the tile-line logo.

The broken line showing of environment is included for the purpose of illustrating only and forms no part of the claimed design.
